UNITED STATES PATENT OFFICE.

WILL S. COFFMAN, OF COLUMBIA, TENNESSEE.

DESIGN FOR A WAGON-BODY.

No. 37,782.

Specification for Design.

Patented Jan. 9, 1906.

Application filed August 14, 1905. Serial No. 274,281. Term of patent 14 years.

To all whom it may concern:

Be it known that I, WILL S. COFFMAN, a citizen of the United States, residing at Columbia, in the county of Maury and State of Tennessee, have invented a new, original, and ornamental Design for a Wagon-Body, of which the following is a specification, reference being had to the accompanying drawing, forming part thereof.

The figure is an elevation of a wagon-body, showing my new design.

I claim—

The ornamental design for a wagon-body, as shown.

WILL S. COFFMAN.
